UNITED STATES PATENT OFFICE

ANDREW M. MCGILL, OF BETHLEHEM, PENNSYLVANIA

APPARATUS FOR RECLAMING JOURNAL PACKINGS

Application filed July 5, 1929. Serial No. 376,236.

The invention relates to the reclamation of journal packing as of oily waste or wool or other fibrous material or a mixture thereof, which has been used as a packing for journal boxes as of railway cars, and it is an object of the invention to provide an apparatus for removing foreign material from used packing of the nature described and for fluffing up the cleansed packing into condition for again saturating with oil for use in journal boxes.

It is a further object of the invention to provide an apparatus of the character referred to which may be operated by a single attendant, the portions of the apparatus being brought together into a single assembly whereby the attendant may put the journal packing through the process of cleaning without moving from one position to another.

It is a further object of the invention to provide an apparatus of the character described having means for fluffing cleansed packing and for removing short fibres and foreign material as pieces of metal therefrom.

It is a further object of the invention to provide an improved process of reclaiming journal packing material.

Further objects of the invention will appear from the following description when read in connection with the accompanying drawings, showing an illustrative embodiment of the invention, wherein:

Figure 1 is a plan view of the apparatus.

Fig. 2 is a front elevation partly broken away, and

Fig. 3 is a detail vertical section on line 3—3 of Fig. 1.

Journal packing of the nature under consideration is usually cotton waste which is saturated with oil and placed in the journal boxes. After a period of use, the packing becomes unfit for use because of the collection of dust, metal cuttings or other particles of metal therein, and because portions of the cotton waste become broken into short fibres which causes the waste to form too dense a mass in the journal box to efficiently apply the oil to the journal. This packing may be reclaimed by removing the oil and foreign matter therefrom and also by removal of the short fibres and by fluffing up the retained

fibrous material when it may be again saturated with oil and reused.

For the purpose of such reclamation, the invention provides a single piece of apparatus wherein all the steps of reclamation of the packing may be carried out. To this end, there is shown a centrifuge comprising a casing 10, having a revoluble basket 11 therein carried by a vertical shaft 12, desirably having a bearing 13 at the bottom of the casing and a bearing 14 adjacent the top thereof. A pulley 15 is shown to which a belt may be applied for revolution of the basket 11.

To prepare the packing for removal of the oil therefrom there is shown a shelf 16, preferably perforated or formed of foraminous material, carried by a wall of the casing 10, brackets 17, 18 being shown to support the shelf. Upon this shelf the material to be treated is placed and picked over by the attendant to remove large chunks of material and to tear to pieces condensed portions of the fibrous material.

The picked over material is then placed into the basket 11 which when charged is caused to revolve at a high rate of speed.

To soften and render fluid the oil in the packing, a steam coil 19 is shown in the bottom of the casing through which steam may be passed to heat the material while it is being subjected to centrifugal action, and oil thus removed from the packing will flow to the bottom of the casing and may be drawn off through a pipe 20.

When all possible oil has been extracted from the material, the material may then be lifted by the attendant out of the basket and placed upon a shelf 21 also carried by the wall of the casing 10. The shelf 21 is shown as perforated or formed of foraminous material. Upon the latter shelf, the material is again picked over to loosen the parts and then foreign material and short fibres are blown therefrom. For this purpose there is shown a perforated head 22 closed at its ends and provided with perforations at its lower portion, and a connection 23 for an air hose 24 is shown connected with the head 22 by means of a T. The head 22 may be supported above the shelf 21 and moved over the ma-

terial by the provision of channel guides 26, 27, in which the ends of the head are adapted to slide. The attendant may operate the blower by grasping the pipe 23 and moving the head in the channels with the compressed air turned on, and as the head is reciprocated over the material, the attendant may carry out additional shaking action by means of his free hand to loosen dirt, dust or other foreign material or short fibres which may be blown through the shelf 21 into a frustoconical chamber 28 from which it may escape through opening 29.

By the assembly of the apparatus shown, an attendant standing in front of the centrifuge between the shelves 16 and 21 may carry out the entire process without moving from his position, thus providing an apparatus adapted to very expeditiously, cheaply and efficiently carry out the entire reclamation of the material.

It is understood that the receptacle in which the material is brought to the apparatus for treatment may be placed by the side of the shelf 16 and a second receptacle for reception of treated material by the side of the shelf 21. The treated material may be lifted from the shelf 21 into the last named receptacle and again saturated with oil ready for shipment to the point of use.

Minor changes may be made in the physical embodiment of the invention without departing from the spirit thereof within the scope of the appended claims.

I claim:

1. Apparatus for reclaiming journal packing comprising a chamber member, a foraminous support disposed over said member, spaced walls extending upwardly from the chamber member providing spaces between their ends for the application, agitation and removal of packing, said walls at a substantial distance above said support having grooves, and a nozzle to discharge air towards said support, said nozzle being guided in said grooves and maintained at a corresponding distance from the support.

2. Apparatus for reclaiming journal packing comprising a chamber member, a foraminous support thereover, walls extending upwardly from the chamber member providing space for the application, agitation and removal of packing, said walls at a substantial distance above said support having grooves open at one end, a nozzle to discharge air towards said support consisting of a perforated pipe guided in said grooves and maintained thereby at a corresponding distance from the support, said pipe being applicable and removable through the open ends of the grooves, and an air supply connection for the pipe disposed intermediate said walls and constituting an operating handle.

ANDREW M. MCGILL.
